UNITED STATES PATENT OFFICE.

JASON H. GREENSTREET, OF INDIANAPOLIS, INDIANA, ASSIGNOR, BY MESNE ASSIGNMENTS, TO WIREBOUNDS CORPORATION, A CORPORATION OF MAINE.

BOX-BLANK MACHINE.

1,325,719.

Specification of Letters Patent. Patented Dec. 23, 1919.

Application filed April 22, 1914. Serial No. 833,599.

To all whom it may concern:

Be it known that I, JASON H. GREENSTREET, a citizen of the United States, residing at Indianapolis, in the county of Marion and State of Indiana, have invented a new and useful Box-Blank Machine, of which the following is a specification.

The object of my invention is to produce a machine for the rapid and economical production of box blanks comprising sheet material and transverse cleats associated by fastening means which may, if desired, comprise binding wires or similar binding members extending lengthwise of the cleat and crosswise of the sheet material, the construction being such that the cleats are accurately spaced by spacing members which are incorporated in the machine and which are brought automatically to a convenient position for insertion between the cleats by the operators who deliver the cleats in proper order to the machine.

The accompanying drawings illustrate my invention. Figure 1 is a plan of a machine incorporating my improvements, the spacing members for one side of the machine having been omitted for clearness of illustration; Fig. 2 a vertical medial section; Fig. 3 a fragmentary plan of the 25 feeder member and associated parts, on a larger scale; Fig. 4 a transverse section on line 4—4 of Fig. 3; Fig. 5 a perspective view of one of the spacer blocks; Fig. 6 a fragmentary plan of a modified form of 30 feeder by means of which the pawls may be readily adjusted; Fig. 7 a fragmentary detail showing the relative arrangement of the cleats, sheets and spacer; Fig. 8 a section on line 8—8 of Fig. 2 but on a larger 35 scale; Fig. 9 a fragmentary vertical section showing the arrangement of sheet carrier relative to the cleats and cleat guides, said sheet carrier being shown in the form which has been found to be convenient in the 40 production of crates as distinguished from tight boxes; Fig. 10 a fragmentary plan of a modified form of spacer block and feeder wherein the feeder acts upon those spacer blocks which space one box blank from another so that the feeding mechanism becomes 45 independent of the cleat lengths; and Fig. 11 a detail of an endless chain feed.

In the drawings, 10 indicates a main frame provided with an anvil 11, superposed 50 stapling mechanism 12, and a main drive

shaft 13. Extending across the anvil 11 and beneath the stapling mechanism 12 are two cleat guides 14 and 15, the cleat guide 14 being preferably laterally fixed while the cleat guide 15 may be laterally adjusted toward and from guide 14 by means of the adjusting screws 16. The construction thus far described is not materially different from that commonly employed in the art, and it is to be understood that the stapling mechanism is operated intermittently to drive staples into the material which will be passed between the stapling mechanism and the anvil 11 so as to fasten said material together. In general the stapling mechanism automatically forms its staples from a supply of wire 17 and straddles these staples over a binding wire 18 which is delivered to the cleat and sheet material of which the box blanks or crate blanks are 75 to be formed. This stapling mechanism and the application of binding wire 18 to the box blanks is well known and forms no part of my present invention, so far as the specific details of construction of the same are concerned.

At the feed end of the machine (the right at Fig. 1) the cleat guides 14 and 15 are extended for a considerable distance so as to have sufficient length to receive enough 85 cleats 25 to form several blanks. This extension is not essential but is desirable to permit the rapid operation of the machine and at various points in the preliminary portion of the cleat guides I provide feed 90 wheels 26 which are arranged to rotate in a substantially horizontal plane and to engage the inner vertical faces of the cleats and drive them forwardly through the cleat guides toward the stapling plane. In practice, cleats 25 vary considerably in width and I have, therefore, found it desirable to mount each feed wheel 26 upon a shaft 27 carried in a bracket 28 journaled upon a horizontal shaft 29, the shaft 27 being provided with a bevel gear 30 meshing with a bevel gear 31 carried by the lower end of shaft 26 and the bracket 28 being urged in one direction by a spring 32 (Fig. 8). The feed wheel 26 is associated with shaft 27 by 100 means of friction disks 33, spring 34 and adjusting nut 35 so that the shafts 27 may be driven constantly at a speed somewhat in excess of the normal forward speed of the cleats so that the feed wheels 26 will serve 105 110

to keep the cleats crowded forwardly in the machine under a yielding force.

Extending along each cleat guide is a spacer block track 41. This track 41 is an endless track beginning at the initial end of the machine and extending beyond the stapling plane. Just beyond the stapling plane, as indicated at 41', the track is deflected laterally away from the cleat guide 10 and then is turned rearwardly and extended back to the initial end of the machine, as clearly indicated in Fig. 1.

Mounted upon each track 41 are many spacer blocks 42 and 43, the blocks 42 being 15 formed for the proper spacing of adjacent cleats of a box blank, while the blocks 43 are formed for the proper spacing between the final cleat of one blank and the initial cleat of the succeeding blank. As a general rule, 20 box blanks are made for common rectangular boxes, and, therefore, the blocks 42 and 43 are arranged in sets of three blocks 42 and one block 43. The precise number of these blocks in any guide is not material, 25 because means can readily be provided to quickly return a block to the initial end of the track as soon as it is withdrawn from between two cleats at the delivery end of the machine, but in practice I have found 30 it convenient to provide a sufficient number of spacer blocks to practically fill the return side of the track, as indicated at the bottom of Fig. 1, and the return is accomplished by means of a reciprocating pawl 35 44 connected to an operating arm 45 which is reciprocated by means of a pitman 46 operated by an eccentric 47 carried by the main drive shaft 13.

The cleats and sheet material are best 40 fed through the machine past the stapling mechanism by some means which is intermittent in its action, so that the sheets and cleats may be stationary during the process of driving the staples, and it is also desirable 45 that the movement of the cleats be in direct proportion to their lengths. Consequently I arrange, near the stapling plane, and adjacent each cleat guide, a guideway 51 parallel with the cleat guide and in this 50 guideway I mount a reciprocating feeder bar 52 which is connected by a link 53 with the reciprocating arm 45. Mounted upon bar 52 is a series of cleat feeding pawls 54 which are normally urged laterally 55 into the cleat guides by light springs 55 and these pawls are so spaced with relation to each other that at least one of them will engage a rear shoulder of one of the cleats 25 before it reaches the stapling plane, the 60 active pawl or pawls 54 thus serving to drive the cleats and interspersed spacer blocks which are in advance of the same to and through the stapling plane. It will be readily understood that where a machine 65 is used for the production of standard sizes

of boxes wherein the cleat lengths are multiples of a common unit, the pawls 54 may be permanently placed upon the bar 52 and that if adjustment is desired, the pawls may be carried upon adjustable blocks 56 such as those shown in Fig. 6 where the blocks 56 are triangular in cross section and set in grooves 57 formed in the upper face of the pusher bar 52, said grooves being flanked by notches 58 into any one of which 75 the block 56 may be set. To adapt the machine for handling cleats of any size and yet insuring a proper placing of the final staples of a blank, I recommend the construction shown in Fig. 10 where the spacer 80 blocks 43 are provided with lateral extensions extending into the path of movement of the pawls 54 of the pusher bar 52, the said pawls being prevented from engaging the cleats by a guard rail 59. By this arrangement, the cleats are advanced through the machine by force exerted against the spacer blocks instead of directly against the cleats.

Where sheet material is to be associated 90 with the cleats to form a tight box the spacer blocks, which embody narrow fingers 95 for projection between the adjacent ends of the cleats, may be provided with upstanding pins 61 which will serve to properly space adjacent sheets and to drive the sheet material forwardly to the stapling plane, this being common practice in machines of this general type. In the present machine, however, I have provided means 100 for associating the slat sheet material 62 with the cleats so as to produce crates and in order to properly associate this slat material with the cleats, I provide adjacent each cleat guide a general guide 63 through 105 which runs an endless chain 64 provided at appropriate intervals with upstanding pins 64' between which the slats 62 may be laid. Chain 64 is arranged substantially in a vertical plane and is passed around suitable 110 idlers 65, 66 and 67. It is essential that the chains 64 move in unison with the cleats and, therefore, each bar 52 is provided with pawls 68 which are adapted to engage the pins 64' of chains 64 and thus advance the 115 chains, and the sheet material, through the machine in unison with the cleats. Each chain guide 63 is provided at its upper edge with a portion 71 which overlies and protects the chain 64 and serves as a support 120 for the slats or sheet material 62. I have found it convenient to incline the chain guides 63 slightly downwardly and forwardly toward the stapling plane so that the top portion 71 beyond the stapling plane 125 will lie a little below the plane of the upper faces of the cleats. This upper surface 71 lies below the upper surface of the cleat an amount equal to or a little greater than the amount of projection of the pins 64' 130

above the surface 71, thus serving to automatically withdraw the pins 64' from between the slats after the slats have been fastened to the cleats.

The operation is as follows:—In starting the machine, two initial cleats of a blank will be placed in the guides 14 and 15 with their initial ends in position to receive the first staples; a spacer block 42 will then be run behind the initial cleat, the second cleat placed behind this block, the second block 42 run in behind the second cleat, a third cleat placed behind the second block 42, a third block 42 placed behind the third cleat; the fourth cleat brought into place, and a block 43 run in behind it. Slats 62 will then be distributed over the cleats between the fingers 64' of the chains 64 and the machine started in operation, the bars 52 operating upon the cleats and slat chains to advance the cleats and slats step by step to and through the stapling plane. In the meantime, the feeding operatives at the initial end of the machine are placing cleats in proper sequence in the cleat guides following each cleat with a spacer block drawn into the cleat guide by hand from the supply on track 41 and these cleats are driven forwardly and kept up against the cleats which are being advanced by the bars 52, by means of the frictionally driven feed wheels 26 which, because of the swinging mounting of the brackets 28 and springs 32, engage the cleats properly even though they vary considerably in width. This swinging movement of the wheels 26, being downwardly, serves to hold the cleats down in the cleat guides.

Just beyond the anvil 11 the track 41 branches off from the cleat guides so that the spacer blocks 42 are automatically retracted from the cleat guide, as clearly shown at the left of Fig. 3 each succeeding block pushing the blocks which preceded it around the curve of the track so that the blocks are finally successively delivered to the pawl 44 which acts upon them to push them along the outer side of the track 41 toward the initial end of the machine where they will be convenient of access by the operatives who place the cleats in place.

Mechanical means might be provided to push the blocks into the cleat guides after introduction of a cleat but in practice I have found that the operatives who place the cleats have ample time to run in the spacer blocks following each cleat without decreasing the capacity of the machine.

It will be understood that other means than the pawl blocks 52 might be provided to drive the cleats through the machine. For instance, as shown in Fig. 11, the cleats may be driven through the cleat guides by endless spur chains 81 arranged to engage 65 the inner vertical faces of the cleats, these

spur chains being advanced step by step by any suitable ratchet mechanism driven in synchronism with the stapling mechanism.

Where the forward feeding of the cleats is accomplished by engagement of the pawls 70 of the pusher bar either with the rear faces of the cleats or by engagement with the successive spacer blocks, it is, of course, essential that all of the pawls of the pusher bar be accurately spaced with relation to the 75 cleat lengths in order that the four cleats of a series may be kept in proper relative arrangement without any more spacing than that provided by the spacer block, and it is therefore necessary that the lengths of the 80 several cleats of any blank be in multiples of the spacing between the pawls on the pusher bar.

By utilizing the construction shown in Fig. 10, however, where the cleat-advancing 85 force is applied only to the rear cleat of each set, the lengths of the cleats need not be considered because all of the cleats of each set will remain compactly together. The driving force might be applied directly 90 to a rear face of the rear cleat of each set, the long spacer block between blanks being then introduced merely to insure a minimum space between blanks but it is more convenient to apply this driving force to 95 every fourth spacer block so as to carry that spacer block forwardly through the machine with the four cleats which immediately precede it.

In this arrangement the spacer blocks will 100 carry the sheet-spacing engaging means and the sheet material may therefore be associated with the cleats accurately and in such manner as to insure a tight edged box when the blank has been folded into final position. 105

The stapling mechanism most commonly in use in machines of this character is one in which the staples are automatically formed and immediately driven as a result of reciprocatory motion derived from a rotating part of the machine and heretofore it has been necessary to move the box material forward one step preliminarily to the driving of each staple, the forward advancement of the box material being equal 110 only to the distance between staples and, as the staples must be driven fairly close together (generally about three inches) in order to produce a substantial box, the number of necessary advancing steps of the material has limited the speed of delivery of the machines because, when these advancing steps are produced too rapidly, there is not only an objectionable jarring of the machinery, but there is also difficulty in stopping the material at regular and desired points and as a consequence the capacity of the machines has heretofore been limited below the ability of the operatives to deliver material to the machines. In my present 115 120 125 130

machine I have overcome this difficulty by arranging over each cleat guide two stapling mechanisms 12, 12 which are spaced apart a distance which is an odd multiple 5 of the distance which is desired between staples. The feeding mechanism is then adjusted so as to intermittently advance the box material through the machine, beneath the stapling mechanism, a distance which is 10 an even multiple of the space desired between the staples. As a consequence, the advancing step of the material may be longer, and therefore less frequent for a given output of the machine, while at the 15 same time maintaining the desired short distance between the staples.

I claim as my invention:

1. In a box blank machine, the combination of a cleat guide, a fixed endless spacer 20 block guide arranged with a portion adjacent and substantially parallel to the cleat guide, and a plurality of independent spacer blocks slidably mounted on said block guide and each provided with a portion formed 25 to traverse the adjacent cleat guide.
2. In a box blank machine, the combination of a cleat guide, and stapling mechanism arranged over said guide and provided with means for operating upon material 30 passing through said guide, a fixed endless spacer block guide arranged with a portion adjacent and substantially parallel to the cleat guide, a plurality of independent spacer blocks slidably mounted on said block 35 guide and having cleat spacing portions to 40 traverse the adjacent cleat guide, and means for advancing the cleats and interspersed blocks through the cleat guide.
3. In a box blank machine, the combination of a cleat guide, a fixed endless spacer block guide arranged with a portion adjacent and substantially parallel to the cleat guide, a plurality of spacer blocks slidably mounted on said block guide and having cleat spacing 45 portions to traverse the adjacent cleat guide, and means for driving the spacer blocks along the spacer block guide in a direction opposite to the movement of the cleats.
4. In a box blank machine, the combination of a cleat guide, a fixed endless spacer block guide arranged with a portion adjacent and substantially parallel to the cleat guide, a plurality of spacer blocks for interspersing with the cleats slidably mounted on 50 said block guide, means for advancing the cleats and interspersed blocks through the cleat guide, and means for driving the spacer block along the spacer block guide in 55 a direction opposite to the movement of the cleats.
5. In a box blank machine, the combination of a cleat guide, an endless spacer block guide arranged in a substantially horizontal 60 plane with one portion adjacent and sub-

stantially parallel with the cleat guide and having another portion laterally displaced relative to the cleat guide, and a plurality of independent cleat-spacing blocks slidably mounted upon said block guide and adapted 70 for introduction between cleats, the arrangement being such that said spacer blocks, when they reach the laterally displaced portion of the spacer block guide, will be automatically withdrawn from the cleat 75 guide and subsequently returned along the block guide to the initial end of the machine.

6. In a box blank machine, the combination of a cleat guide, a spacer block guide 80 having a portion adjacent and substantially parallel with said cleat guide and having another portion laterally displaced from said cleat guide and another portion connecting with said last-mentioned portion and returned to the initial end of the machine, and a plurality of independent spacer blocks slidably mounted upon said spacer block guide for interspersing with cleats.

7. In a box blank machine, the combination of a cleat guide, a spacer block guide having a portion adjacent and substantially parallel with said cleat guide and having another portion laterally displaced from 90 said cleat guide and another portion connecting with said last-mentioned portion and returned to the initial end of the machine, a plurality of independent cleat spacing blocks slidably mounted upon said block 95 guide, and means for driving said blocks along the return portion of the spacer block guide toward the initial end of the machine.

8. In a box blank machine, the combination with a cleat guide and stapling mechanism arranged over said guide and provided 105 with means for operating upon material passing through said guide, of a feed bar reciprocably mounted adjacent and substantially parallel with said cleat guide, a plurality of closely spaced pawls carried by 110 said feed bar and arranged to engage in one direction material lying in the cleat guide, a series of independent spacer blocks each having a portion adapted for projection into the cleat guide, and an endless guide for said 115 spacer blocks having a portion substantially parallel with the cleat guide and arranged to cause projection of portions of the spacer blocks into the cleat guide when the spacer blocks traverse the same.

9. In a box blank machine, the combination with a cleat guide, of a feed bar reciprocably mounted adjacent and substantially parallel with said cleat guide, a plurality of pawls carried by said feed bar and arranged 125 to engage in one direction material lying in the cleat guide, a carrying chain arranged adjacent and substantially parallel with the cleat guide and provided with a plurality of sheet-engaging members, and pawls car- 130

- ried by the feed bar for engaging said carrying chain and moving the same in synchronism with the movement of material through the cleat guide.
- 5 10. In a box blank machine, the combination with a cleat guide, of a feed wheel arranged to engage one of the vertical faces of cleats in the cleat guide to drive the cleats longitudinally of the cleat guide, a shaft 70 carrying said feed wheel, a bracket supporting said shaft and movable toward and from the cleat guide, means for yieldingly urging said bracket toward the cleat guide, and driving gearing associated with said shaft 15 and bracket to rotate the feed wheel in various positions of the bracket.
11. In a box blank machine, the combination with a cleat guide and stapling mechanism arranged over said guide and provided 20 with means for operating upon material passing through said guide, a feed bar reciprocably mounted adjacent and substantially parallel with the cleat guide, a series of independent spacer blocks each having a 25 portion adapted for projection into the cleat guide, an endless guide for said spacer blocks having a portion substantially parallel with the cleat guide and arranged to cause projection of portions of the spacer 30 blocks into the cleat guide when the spacer blocks traverse the same, and means carried by said feed bar for exerting a driving force lengthwise of the cleat guide upon rear faces of material in the cleat guide.
- 35 12. In a box blank machine, the combination with means for feeding material including cleats, of a cleat guide; a chain guide beside the cleat guide extending longitudinally thereof but declined relatively 40 in a plane at right angles to the plane of movement of the work; an endless chain passing through said chain guide and provided with a plurality of sheet-engaging members; and means for synchronously 45 driving cleats and said chain comprising a reciprocating feed-bar provided with cleat-feeding pawls and with chain-feeding pawls.
13. A machine of the class described comprising, in combination, mechanism for fastening together the cleats and side material of assembled box or crate sections and to secure binding wire thereto; and means for presenting such sections thereto with the parts in proper relationship, comprising 55 separate and independent cleat and sheet forwarding devices, and a common actuating means for synchronously advancing said cleat and sheet forwarding devices.
14. A machine of the class described having, in combination, cleat-feeding means; separate and independent feeding means for side material associated with cleats; and a common actuating means for operating them synchronously.
15. In a box blank machine, an endless

spacer block guide extending lengthwise of the line of movement of material through the machine, a plurality of sets of independent spacer blocks slidably mounted upon said guide and movable along the same, and step-by-step driving means for advancing said spacer blocks and interspersed material lengthwise of said guide.

16. In a box blank machine, a spacer block guide extending lengthwise of the line of movement of material through the machine, a plurality of sets of spacer blocks slidably mounted upon said guide and movable along the same, step-by-step feeding means, and means acting upon the rear spacer block of each set for advancing said spacer blocks and interspersed material lengthwise of said guide.

17. In a box blank machine, the combination with means for guiding cleats and associated sheet material therethrough, of stapling mechanisms arranged to staple the sheets and cleats together, said stapling mechanisms arranged in pairs longitudinally of the travel of material through the machine, and means for advancing the material through the machine successive distances less than the distance between the pairs of stapling mechanisms whereby staples may be placed at distances apart less than the distance of intermittent advancement of the material.

18. In a box blank machine, the combination with means for guiding the cleats and associated sheet material therethrough, of stapling mechanisms arranged to staple the sheets and cleats together, said stapling mechanisms arranged in pairs longitudinally of the travel of material through the machine and in each pair a distance apart which is an odd multiple of the desired distance between the staples, and means for advancing the material through the machine successive distances equal to an even multiple of the desired distance between the staples.

19. In a box blank machine, the combination of a cleat guide, a spacer block guide substantially parallel with the cleat guide and provided with a lateral extension extending away from the cleat guide in substantially the same horizontal plane, a plurality of groups of independent spacer blocks slidably mounted on said block guide and adapted for interspersing with cleats, each of said groups comprising as many blocks as there are independent sections in the blank to be produced and one of each group of blocks having a longitudinal extent materially greater than the other blocks, and means for advancing the cleats and interspersed blocks through the cleat guide.

20. In a box blank machine, the combination of a cleat guide, a spacer block guide

arranged adjacent and substantially parallel with the cleat guide and provided with a lateral extension extending away from the cleat guide in substantially the same horizontal plane, a plurality of independent spacer blocks slidably mounted on said block guide and each provided with a portion formed to project into and traverse the adjacent cleat guide, and means for advancing the cleats and interspersed blocks through the cleat guide.

21. In a box blank machine, the combination of a cleat guide, a spacer block guide substantially parallel with the cleat guide and provided with a lateral extension extending away from the cleat guide in substantially the same horizontal plane, and a plurality of groups of independent spacer blocks adapted for introduction into the cleat path slidably mounted on said block guide, each of said groups comprising as many blocks as there are independent sections in the blank to be produced and one of each group of blocks having a longitudinal extent materially greater than the other blocks.

22. In a box blank machine, the combination of a cleat guide, a spacer block guide substantially parallel with the cleat guide and provided with a lateral extension extending away from the cleat guide in substantially the same horizontal plane, and a plurality of independent spacer blocks slidably mounted on said block guide formed to traverse the adjacent cleat guide.

23. In a box blank machine, the combination of a cleat guide, a plurality of independent spacer blocks for traversing the cleat guide, a fixed endless spacer block guide arranged to support the spacer blocks so that they may traverse the cleat guide, means for laterally withdrawing the spacer blocks from the cleat guides substantially in the same horizontal plane with said guides, means for advancing the cleats and interspersed blocks through the cleat guide, and means for driving the spacer blocks along the block guide in a direction opposite to the movement of the cleats.

24. In a box blank machine, the combination of a cleat guide, a plurality of independent spacer blocks for traversing the cleat guide, a fixed endless spacer block guide arranged to support the spacer blocks so that they may traverse the cleat guide, means for laterally withdrawing the spacer blocks from the cleat guides substantially in the same horizontal plane with said guides, and means for advancing the cleats and interspersed blocks through the cleat guide.

25. In a box blank machine, the combination of a cleat guide, a plurality of independent spacer blocks for traversing the cleat guide, a fixed endless spacer block

guide arranged to support the spacer blocks so that they may traverse the cleat guide, means for laterally withdrawing the spacer blocks from the cleat guides substantially in the same horizontal plane with said guides, and means for driving the spacer blocks along the block guide in a direction opposite to the movement of the cleats.

26. In a box blank machine, the combination of a cleat guide, a plurality of independent spacer blocks for traversing the cleat guide, a fixed endless spacer block guide arranged to support the spacer blocks so that they may traverse the cleat guide, and means for laterally withdrawing the spacer blocks from the cleat guides substantially in the same horizontal plane with said guides.

27. In a box blank machine, the combination with means for connecting together box blank materials, of guides for delivering such materials to the fastening means, and two sets of independent spacer blocks to engage and properly space the box blank materials on their way to the said connecting means, a fixed endless guide for each of said sets of spacer blocks, said endless guide being arranged in a plane substantially parallel with the box material guides, and means independent of said guides for driving the box blank materials and interspersed spacer blocks through the box material guides to the said connecting means.

28. In a box blank machine, the combination with means for connecting together box blank materials, of guides for delivering such materials to the said connecting means, and two sets of independent spacer blocks to engage and properly space the box blank materials on their way to the fastening means, a fixed endless guide for each of said sets of spacer blocks, and means independent of said guides for driving the box blank materials and interspersed spacer blocks through the box material guides to the said connecting means.

29. In a box blank machine, the combination with means for connecting together box blank materials, of guides for delivering such materials to the said connecting means, and two sets of independent spacer blocks each having portions formed to engage and properly space the box blank materials on their way to the said connecting means, a fixed endless guide for each of said sets of spacer blocks, said endless guide being arranged in a plane substantially parallel with the box material guides, and means independent of said guides for driving the box blank materials and interspersed spacer blocks through the box material guides to the said connecting means, each set of spacer blocks comprising a plurality of similar groups, each group comprising as many spacer blocks as there are sections in the

box blank to be produced and each group having one block of greater longitudinal extent, as to its material-spacing portion, than the other blocks of the group.

- 5 30. In a box blank machine, the combination with means for connecting together box blank materials, of guides for delivering such materials to the said connecting means, and two sets of independent spacer blocks to engage and properly space the box blank materials on their way to the said connecting means, a fixed endless guide for each of said sets of spacer blocks, and means independent of said guides for driving the box blank materials and interspersed spacer blocks through the box material guides to the said connecting means, each set of spacer blocks comprising a plurality of similar groups, each group comprising 10 as many spacer blocks as there are sections in the box blank to be produced and each group having one block of greater longitudinal extent, as to its material-spacing portion, than the other blocks of the group.
- 15 31. In a box blank machine, the combination of mechanism for fastening the blank materials together, guides for guiding the box blank material to said fastening mechanism, two sets of independent spacer blocks 20 each comprising a plurality of groups of spacer blocks and each group equaling in number the number of sections of the desired box blank, means for supporting the spacer blocks to cause them to traverse the 25 box material guides during a portion of their travel and to return to initial position during another portion of their travel, and means for continuously driving the materials for successive box blanks and interspersed spacer blocks through the box material guides to the fastening mechanism.

32. In a box blank machine, the combination with means for guiding blank-forming materials therethrough, of fastening mechanisms arranged to connect such materials into a foldable box blank, said fastening mechanisms arranged in pairs longitudinally of the travel of material through the machine, and means for advancing the 40 material through the machine by successive steps, each step being less than the distance between the fastening mechanisms of a longitudinally arranged pair, whereby fastenings may be placed at distances apart 45 less than the distance of intermittent advancement of the material.

33. In a box blank machine, the combination with means for guiding blank-forming materials therethrough, of fastening mechanisms 45 arranged to fasten said materials together into a foldable box blank, said fastening mechanisms arranged in pairs longitudinally of the travel of material through the machine and in each pair at a distance 55 apart which is an odd multiple of the desired

distance between the fastenings in each box blank, and means for advancing the materials through the machine by successive steps, each step being equal to an even multiple of the desired distance between the 70 fastenings.

34. A box blank machine comprising spacing blocks for insertion between the ends of the cleats, means for wiring the sections of the blank together, and means independent 75 of timed relation to the wiring mechanism and disposed in position to receive the oncoming blocks operating automatically to cause the forcible displacement of said blocks from the blanks.

35. A machine for making box blanks by successively wiring together the side material and cleats forming the previously unconnected side parts of each blank, to produce a flexible blank as the immediate result of said wiring operation, comprising 85 staplers for applying the binding wires, spacing blocks for insertion between the ends of the cleats, guides for said blocks and cleats, said guides and blocks being relatively formed to prevent upward displacement of the blocks from the guides, and feeding means for causing said blocks and cleats to move along said guides, and means independent of timed relation to the wiring 90 and feeding means to withdraw automatically the blocks from between the cleats.

36. A box blank machine comprising, in combination, wire securing mechanism for foldably connecting side material and cleats 100 to produce a foldable blank; spacing blocks for insertion between cleats; guides for said cleats; distinct parallel guides for the spacer blocks offset laterally from the cleat guides; said latter guides and spacer blocks shaped 105 for interlocking sliding engagement; and feeding means for causing said blocks and cleats to advance to said mechanism.

37. A machine for making box-blanks by wiring together side material and cleats, 110 comprising mechanism to apply the binding wires; spacing blocks for insertion between the cleats; feeding means for causing progression of the work and spacing blocks; work-guiding means; and an automatic spacing block extractor comprising a rigid block-engaging deflector.

38. A machine for making box-blanks by wiring together side material and cleats, 115 comprising mechanism to apply the binding wires; spacing blocks for insertion between the cleats; feeding means for causing progression of the work and spacing blocks; work-guiding means; and a track slidably engaged by the spacing blocks and having 120 a deflection to extract the spacing blocks from the cleats.

39. A machine for making box-blanks by wiring together side material and cleats, 125 comprising mechanism to apply the binding 130

- wires; spacing blocks for insertion between the cleats; feeding means for causing progression of the work and spacing blocks; work-guiding means; and a track slidably engaged by the spacing blocks and having a deflection to extract the spacing blocks from the cleats and a continuous return portion formed for reintroducing the spacing blocks into the path of cleats.
40. A box-blank machine comprising, in combination, means to secure binding wire to box parts; means for feeding thereto a succession of box parts and interspersed spacing devices; said spacing devices; and a track slidably engaged by said spacing devices and having a deflection to withdraw the spacer blocks successively from between the box parts.
41. A box-blank machine comprising, in combination, mechanism including wiring means for operating upon blank materials to produce a blank; material-feeding means including means controlling the movement of an advanced portion of the materials relative to said mechanism and means yieldingly urging succeeding materials toward such advanced portion at a relatively faster rate for crowding materials in loose assembly into proper blank-forming relationship as they feed to said mechanism; a plurality of independently movable spacing devices traveling in orbits and adapted for successive introduction behind successively introduced blank parts; endless tracks slidably engaged by said spacing devices, formed to introduce them into the path of said parts at the receiving end of the machine and formed with block-extracting deflections at the delivery end.
42. In a box blank machine, the combination with means for feeding and guiding cleats and interspersed spacer blocks, of a rigid block-engaging deflected track to extract said blocks from the cleats.
43. In a box blank machine, the combination of a cleat guide, spacing blocks for insertion between cleats, separate and independent sheet-spacing devices, and a common means for advancing said blocks, devices and associated work.
44. In a box blank machine, the combination of a cleat guide, spacing devices for insertion between cleats, separate and independent sheet spacing devices, and a common work-feeding means arranged longitudinally therebetween.
45. A box blank comprising, in combination, binding-wire applying means; means for supporting and guiding the work for progressive presentation to said wire-applying means; a plurality of groups of spacing blocks for determining relative positions of adjacent cleats during such presentation; and reciprocating feeding means constructed and arranged for progressive feeding engagement with each of corresponding end spacing blocks of said groups in succession for advancing the work and spacer blocks to the wire-applying means.
46. A box blank machine comprising, in combination, wire-securing mechanism for operation upon box parts; means for supporting and guiding a succession of box parts for progressive presentation to said wire-securing means; a plurality of groups of spacing devices for determining relative positions of adjacent box parts during such presentation; and a reciprocatory feeder bar having a series of pawls arranged to engage propulsively corresponding end spacing devices of each group in turn for advancing the work and the spacing devices to said wire securing means.
47. A box-blank machine comprising, in combination, mechanism including wiring means for operating upon blank materials to produce a blank; means for progressively advancing thereto materials for successive blanks including traveling positioning devices related to the ends of the blanks to maintain a desired relationship therebetween; and reciprocating feeding means constructed and arranged for a series of propulsive engagements with such positioning devices in sequence to cause advance of the work thereby.
48. A box-blank machine comprising, in combination, mechanism including wiring means for operating upon blank materials to produce a blank; means for progressively advancing thereto materials for successive blanks, including traveling positioning devices related to the ends of the blanks to determine their relative positions; and a reciprocating feeder-bar having a set of feed pawls for successively engaging such positioning devices in turn to cause propulsion of the work thereby.
49. A box blank machine comprising, in combination, mechanism including wiring means for operating upon blank materials to produce a foldable blank; means for supporting and guiding materials for progressive presentation of successive blanks; members traveling with the work similarly correlated with corresponding ends of successive blanks, having their relative positions determined by the said blank ends; and a reciprocating feeder bar having a set of feed pawls for successively propulsively engaging said members in turn, to cause step-by-step feed of the work.
50. A box blank machine comprising, in combination, binding-wire applying mechanism; work-forwarding means adapted for determining desired relative positions of successive blanks during a progressive presentation to said mechanism; a step-by-step feeding means for imparting a series of movements to move a blank to a series of

positions for successive attachment of the binding wire; and means causing said series of imparted movements to be directly applied successively to work-forwarding means 5 at corresponding locations relative to successive blanks.

51. A box blank machine comprising, in combination, binding-wire applying mechanism; means for supporting and guiding successive blanks for a progressive delivery 10 to said mechanism; a step-by-step feed mechanism for imparting a series of movements to move a blank to a series of positions for successive attachment of the binding wires; means causing said series of movements to be applied successively to the rear ends of successive blanks; the machine being organized 15 for forwarding successive blanks at desired relative positions in unison.

52. A box blank machine comprising, in combination, binding-wire applying mechanism; means for maintaining desired relative positions of successive blanks during a progressive presentation to said mechanism, 20 including work-engaging members associated with ends of the blanks; and means constructed and arranged for direct coöperation with said members in succession to impart to each a series of movements for moving the 25 corresponding blank to a series of positions for application of the binding-wire thereat.

53. A box blank machine comprising, in combination, binding-wire applying mechanism; work-forwarding means adapted for 30 maintaining desired relative positions of successive blanks during a progressive presentation to said mechanism; and a reciprocating feed bar having a series of pawls for imparting a series of movements to present a 35 succession of points on a blank to said binding-wire applying mechanism; said feed bar arranged to impart said series of movements successively to work-engaging means at corresponding relative locations to successive 40 blanks.

54. A box blank machine for wiring successive blanks in a desired spacial relationship,—which comprises, in combination, mechanism for applying the binding wires; work-forwarding means adapted for maintaining such spacial relationship of successive blanks during a progressive presentation 45 to said wire-applying mechanism; means to impart a series of step movements for presenting successive points of a blank to the operation of said wire-securing means; certain members of the work-forwarding means which are similarly correlated with successive blanks being adapted for successively coöoperating with said motion-imparting means to predetermine a given relationship between the wire-applying mechanism 50

and each blank at the initiation of such series of movements for said blank.

55. A box blank machine for wiring successive blanks in a desired spacial relationship,—which comprises, in combination, mechanism for applying the binding wires; work-forwarding means adapted for maintaining such spacial relationship of successive blanks during a progressive presentation 60 to said wire-applying mechanism; means comprising a reciprocating feed bar having a series of feed pawls to impart a series of step movements for presenting successive points of a blank to the operation of said wire-securing means; certain members of the work-forwarding means which are similarly correlated with successive blanks being adapted for successively coöoperating 65 with said feed bar to predetermine a given relationship between the wire-applying mechanism and each blank at the initiation of such series of movements for said blank.

56. A machine for use in making wire-bound boxes comprising, in combination, means for wiring box parts including a plurality of instrumentalities for operating at different points in the length of the binding wire spaced a multiple of a desired distance 70 between adjacent wire-securing points; and means to cause relative progression between said wire-securing means and the work in steps another multiple of such distance.

57. A machine for use in making wire-bound boxes comprising, in combination, means to secure binding wire to box parts including a plurality of instrumentalities for operating at different points in the length of the wire; and means to cause relative step movements between said wire-securing means and the work; said step movements and the space between points of operation of said instrumentalities being different multiples, one odd and the other even, of a given 80 spacing for adjacent wire fastenings.

58. The combination of fastener-setting mechanisms arranged one behind another in the direction of relative work movement; and means for relatively moving said mechanisms and the work step-by-step; the step movements and the space between said mechanisms being different multiples, one odd and one even, of a desired spacing for successive fastening points.

In witness whereof I have hereunto set my hand at Indianapolis, Indiana, this 15th day of April, A. D. one thousand nine hundred and fourteen.

JASON H. GREENSTREET.

Witnesses:

ARTHUR M. HOOD,
G. B. SCHLEY.

DISCLAIMER.

1,325,719.—*Jason H. Greenstreet*, Indianapolis, Ind. **BOX-BLANK MACHINE.** Patent dated December 23, 1919. Disclaimer filed July 28, 1920, by the assignee, by mesne assignments, *Wirebounds Patents Company*.

Enters this disclaimer—

“To claims 13, 14, and 43 of said patent, which are in the following words, to wit:

“13. A machine of the class described comprising, in combination, mechanism for fastening together the cleats and side material of assembled box or crate sections and to secure binding wire thereto; and means for presenting such sections thereto with the parts in proper relationship, comprising separate and independent cleat and sheet forwarding devices, and a common actuating means for synchronously advancing said cleat and sheet forwarding devices.

“14. A machine of the class described having, in combination, cleat-feeding means; separate and independent feeding means for side material associated with cleats; and a common actuating means for operating them synchronously.

“43. In a box blank machine, the combination of a cleat guide, spacing blocks for insertion between cleats, separate and independent sheet-spacing devices, and a common means for advancing said blocks, devices and associated work.”
